INFEED CYCLE CONTROL MECHANISM FOR
GRINDING MACHINES

Raymond D. Wortendyke, Cincinnati, Ohio, assignor to Cincinnati Grinders Incorporated, Cincinnati, Ohio, a corporation of Ohio

Application July 25, 1938, Serial No. 221,051

14 Claims. (Cl. 51—105)

This invention relates to machine tools, and more particularly to improvements in grinding machines.

One of the objects of this invention is to provide an improved automatic infeed mechanism for grinding machines.

Another object of this invention is to provide a mechanism of the character described which is relatively economical to construct and operate.

10 A further object of this invention is to provide an infeed cycle control apparatus which may be built as a separate unit for application to new or existing grinding machines.

15 An additional object of this invention is to provide an automatic infeeding mechanism which will execute a complete cycle of operation including rapid traverse advance, variable feed, tarry and rapid return and stop.

20 Other objects and advantages of the present invention should be readily apparent by reference to the following specification considered in conjunction with the accompanying drawings illustrative of one embodiment thereof, but it will be understood that any modifications may be 25 made in the specific structural details within the scope of the appended claims without departing from or exceeding the spirit of the invention.

Referring to the drawings in which like reference numerals indicate like or similar parts:

30 Figure 1 is a plan view of a grinding machine in which this invention has been embodied.

Figure 2 is a sectional view on the line 2—2 of Figure 1.

Figure 3 is a section on the line 3—3 of Figure 2.

Figure 4 is a section on the line 4—4 of Figure 2.

Figure 5 is a section on the line 5—5 of Figure 2.

40 Figure 6 is a section on the line 6—6 of Figure 2.

Figure 7 is a detail view of the hydraulically actuated limit switch for controlling rotation of the workhead.

45 Figure 8 is a detail view of the workhead chuck operating cylinder.

Figure 9 is a diagrammatic view of the hydraulic control circuit showing the interconnection with the hydraulic elements shown in Figures 3, 4, 5, 6, 7 and 8.

50 Figure 10 is a diagram of the hydraulic cycle control circuit.

As an example of a machine to which this invention is applicable, there is shown in Figure 55 1 of the drawings a grinding machine having a

bed 10, a work support 11, a grinding wheel 12, and a support 13 for the grinding wheel which is oscillatably mounted on the bed for moving the grinding wheel toward and from the work support.

The oscillating movement of the grinding wheel support may be divided into two components, one of which is a rapid traverse movement effected by a hydraulic jack whereby the grinding wheel is moved from a work loading to a grinding position; and a feeding movement effected by a rotatable cam having the necessary contoured surface for completing the infeeding movement of the grinding wheel during a fixed angular rotation of the cam.

The machine structure thus far described corresponds in general to the machine shown in U. S. Patent 2,025,885.

This invention deals with means for effecting an infeeding cycle of a grinding wheel and comprises, in general, a manual control lever, a power relay mechanism for reproducing the movements of the lever in the cam, and an automatic cycle control mechanism for effecting automatic power movement of the lever.

The grinding wheel is secured to the end of a spindle 15 which is journaled in the support 13. The support oscillates about an axis 16 located below the axis of the spindle in such a manner that counterclockwise motion of the support will move the grinding wheel toward the work piece and clockwise motion will move the grinding wheel away from the work piece. The hydraulic jack, which effects the initial or rapid traverse movement of the grinding wheel from its retracted or work loading position, comprises a piston 17 and a cylinder 18, the latter being formed integral with the grinding wheel support. A piston rod 19 projects through one end of the cylinder into engagement with one end of a plunger 20 which is reciprocably guided in a fixed part of the bed 10. The plunger has an anti-friction roller 20' which engages the periphery of a feed control cam.

Channels 21 and 22 are connected to opposite ends of the cylinder 18, as shown in Figure 2, so that when fluid pressure is admitted to channel 21, the pressure created in the upper end of the cylinder will cause counterclockwise motion of the grinding wheel, and when fluid pressure is admitted to channel 22, the opposite effect will be produced.

The actuating mechanism is so designed that it may be controlled by a single member, one oscillation of which will result in a complete

grinding cycle, beginning at the work loading position of the grinding wheel and terminating at the same position. This common control comprises a lever 23, which, as shown in Figure 2, 5 is fixed to the end of shaft 24 supported for rotation on antifriction bearings 25 carried by the bed of the machine.

One end of shaft 24 is provided with a head 26 in which is mounted a crank pin 27 projecting 10 into a radial slot 28 formed in the sleeve 29 of a servo-valve indicated generally by the reference numeral 30. The servo-valve has a housing 31 which is held against rotation by a set screw 32 threaded in the bed of the machine. A 15 co-axial main shaft 33 has a portion 34 which passes through the center of the servo-valve and is journaled in an antifriction bearing 35 formed in the head 26. The main shaft serves as a feed-back connection from a servo-motor to the servo- 20 valve.

The housing 31, as shown in Figure 6, has four ports 36, 37, 38 and 39 which are in constant communication with corresponding annular grooves axially spaced along the periphery of the sleeve 29. Each groove has a pair of diametrically opposite radial ports formed therein for establishing communication with the interior of the sleeve. There are four pairs of these ports, each pair being angularly advanced 45° 25 with respect to the preceding pair. The inner member 34 is provided with four longitudinal grooves 40, 41, 42 and 43 separated by lands 44, 45, 46, and 47.

The ports 36 and 38 are connected by channels 48 and 49 to opposite ends of a servo-motor cylinder 50 having a contained piston 51, which is connected by a piston rod 52 extending through one end of the cylinder to a crank arm 53. The crank arm is keyed to the main shaft 40 33. The port 37 is connected by channel 54 to the output of a constant delivery pump 55.

The port 39 is connected by channel 56 to port 57 of a low pressure relief valve 58. The channel 56 has a branch connection with the port 59 45 of this valve whereby the pressure in the channel will shift the plunger 60 against the resistance of spring 61 to interconnect port 57 with port 62 which is connected to reservoir through channel 63.

50 It will now be apparent that if the port 37 of the servo-valve is a pressure port and the port 39 is an exhaust port that the opposing lands 44 and 46 will close the exhaust port, while the opposing lands 45 and 47 will close the pressure port 45 whereby the parts will be at rest. Upon rotation of the sleeve 29 in a clockwise direction, the radial bores 37' will move out of alignment with the lands 45 and 47, and pressure fluid will flow into the grooves 41 and 43. From here the fluid will flow through port 38, and channel 49 to the right hand end of cylinder 50, causing clockwise rotation of shaft 33 through the described interconnections. Fluid from the other end of cylinder 50 will flow through channel 48, 65 and port 36, to the opposing spaces 40 and 42. Since the opposing radial bores 37' have been moved clockwise out of registry with the lands 44 and 46, the fluid in the spaces 40 and 42 will return to reservoir through channel 56.

70 It will now be apparent that a clockwise movement of the sleeve will cause actuation of the servo-motor, but the servo-motor will rotate the shaft 33 in a clockwise direction and thereby cause rotation of the center portion 34 of the 75 servo-valve in a direction to follow up the move-

ment of the sleeve and thereby re-establish the stop position of the parts and thus stop the motor. Therefore, in order to have the movement of the motor continuous, it is necessary to maintain a continuous movement or rotation of the sleeve 29. This servo-motor mechanism acts as a power relay between the manual control 23 and the shaft 33.

Rotation of the shaft 33 in a clockwise direction will cause rotation of a crank 64 through 10 yieldable friction means comprising discs 65 and 66 keyed to the shaft 33 on opposite sides of the crank, and held into frictional engagement with the crank by means of spring 67 which surrounds the shaft. Adjustment of the spring is made by 15 a nut 68 threaded on the shaft. The object of this friction connection is that upon initial rotation of the shaft, the crank 64 will be moved through a predetermined angular distance to effect shifting of plungers 69 and 70 which are 20 connected by an equalizing yoke 71 to a rod 72 pivotally connected to the end of the crank. The ends of the yoke 71 have a lost motion connection with the plungers 69 and 70. These plungers are normally held in an upward position by springs 73 which are interposed between the lower end of the plungers and the bottom of the valve housing 74 which contains them.

The plunger 70 is a reversing valve plunger for controlling the admission of fluid pressure to the 30 hydraulic jack cylinder 18. As previously mentioned, this cylinder has a pair of channels 21 and 22 and these channels are connected to ports 75 and 76 of valve housing 14. There is also a pressure port 77 intermediate these ports and a 35 pair of exhaust ports 78 and 79 on the opposite sides thereof. The plunger has two annular grooves 80 and 81 whereby when the plunger is in the position shown, the pressure port is connected to channel 22 and the wheel housing is 40 returned. Upon initial rotation of the shaft 33, the lost motion between the yoke 71 and the shoulder 82 on the plunger 70 is taken up, after which the plunger is depressed to connect the pressure port 77 to port 75 whereby fluid will enter cylinder 18 through channel 21 and cause 45 rapid traverse movement of the grinding wheel support in a counterclockwise direction. At the same time, fluid will flow through a branch 21' to an operating cylinder 196 for a limit switch, 50 closing the same to cause rotation of a headstock motor 196'.

The valve plunger 69 is a reversing valve plunger for automatically controlling a work 55 chuck when the same is utilized for holding work and is operated in the same manner and simultaneous with the reversing valve plunger 70. The plunger 69 controls the flow of fluid pressure to and from a chuck operating cylinder 83 through channels 84 and 85. The cylinder has 60 a contained piston 84' which is connected by a piston rod 85' for operating the chuck.

Thus, rotation of the hand lever 23 will cause actuation of the servo-motor piston 51, which in turn will rotate the shaft 33. This rotation will 65 continue as long as the handle 23 is actuated and until the piston 51 reaches the end of its cylinder. Rotation of the shaft 33 will cause shifting of the reversing valve plungers 69 and 70 causing automatic closing of the work chuck and rapid 70 traverse movement of the grinding wheel into a grinding position, after which the grinding wheel will continue to be fed in by means of a cam 86 which is keyed to the shaft 33 and in co-planar relation with the plunger 20.

After the grinding wheel has completed its inward movement and ground the work to size, the lever 23 is reversed, causing the piston 51 to return and effect counterclockwise rotation of the shaft 33. Attention is invited to the fact that the friction clutch, which drives the crank 64, will slip after the plungers 69 and 70 have reached the limit of their downward stroke, but upon reversal of shaft 33, the plungers will immediately follow up, causing immediate release of the work chuck and rapid traverse retraction of the grinding wheel. After the plungers have reached the limit of their stroke, the crank will move a further distance dependent upon the amount of lost motion. Attention is invited to the fact that the unit pressure of the fluid supplied to the chuck operating cylinder 83 does not have to be as great as that supplied to other parts of the system, and therefore a reducing valve 87 is provided, having a pressure port 88 which is connected to the pump 55, and a delivery port 89 which is connected by channel 90 to port 91 of the chuck control valve 69. The reducing valve has a spring pressed plunger 92 in which is formed an annular groove 93 of such width that it partially closes each of the ports 88 and 89 thereby causing a reduction in pressure in two steps. A branch connection from channel 90 through a choke coil 94 is made to the upper end of the valve housing for actuation of a piston 95 in opposition to the spring 96. Thus, if the pressure rises in the channel 90 beyond a predetermined amount, the plunger 92 will be caused to move downward further restricting the pressure port 88 and causing a greater drop in pressure.

The main pressure in the system may be controlled by a valve 97 having a port 98 which is connected to the pump delivery line 54 and an exhaust port 99 which is connected to the exhaust line 56. The valve plunger 100 is continuously urged by a spring 101 into a position to close the exhaust port 99 but should the occasion arise that the pressure in channel 54 should go above a predetermined amount, said pressure will be communicated through a resistance coil 102 to a plunger 103 reciprocably mounted in the upper end of the valve housing 97 to urge the plunger 100 downward against the resistance of spring 101 and thereby open the exhaust port 99 whereby a certain amount of fluid will by-pass to reservoir and thus lower the pressure in the delivery channel 54.

As has been mentioned supra, the infeeding cycle may be effected by rotation of the hand lever 23, but since this necessitates the continuous attention of the operator at all times, and since uniform timing can not be obtained if dependence is placed upon manual operation, a power operated driving and timing mechanism has been provided for actuation of the manual control lever, thus insuring uniformity for each cycle of operation. This cycle control mechanism includes a fluid operable motor comprising a cylinder 104 having contained piston 105 which is operatively connected by a piston rod 106 to a crank arm 107. The crank arm is keyed to shaft 108 which has a second crank arm 109 connected by a link 110 to a crank 111 integral with the manually operable lever 23. The cylinder 104 has a pair of ports 112 and 113 located in opposite ends thereof and connected by channels 114 and 115 respectively to ports 116 and 117 of a regenerative valve 118.

Pressure fluid for operation of the motor 104 is supplied by the pump 55 through a channel 119 which is a branch of the main delivery channel

54. The channel 119 is connected to port 120 of a pilot valve 121 and to port 122 of the reversing valve 123. The reversing valve 123 has a fluid shiftable plunger 124, the position of which is controlled by the pilot valve 121. When the plunger 124 is shifted to the right, the port 122 is connected by the cannelure 125 to port 126 whereby the fluid pressure will flow through channel 127 to ports 128 and 129 of the regenerator valve 118. When the regenerative valve plunger 130 is 10 in the position shown, the port 128 is connected to the motor port 117 whereby fluid pressure will flow to the right hand end of cylinder 104 causing actuation of piston 105. The fluid from the other end of the cylinder will return through channel 114 to port 116 of the regenerative valve which at this time is connected by cannelure 131 to port 132 whereby the fluid will continue through channel 133 to port 134 of the reversing valve. With plunger 124 in a right hand position, the 15 port 134 will be interconnected with port 135 whereby the returning fluid will continue through channel 136 to port 137 of the rate control valve 138, and to port 139 of the "run ahead" valve 140. The rate control valve has an adjustable plunger 141 which is held against the end of an adjusting shaft 142 by a spring 143. Shaft 142 is threaded at 144 in the housing 138 and rotated by the knurled knob 145. The plunger 141 has a spool 146 in which is formed a V-notch 147 movable 20 relative to the port 137 for regulating the flow therethrough. This constitutes a form of hydraulic resistance which varies the back pressure in channel 136 and thereby in the cylinder 104. 25

After the fluid passes the hydraulic resistance 30 formed by the notch 147, it collects in an annular groove 148 formed in the plunger which is in constant communication with a port 149. This port is connected to an exhaust channel 150 through which the fluid is returned to the exhaust line 56 35 of Figure 7 and thereby to the common reservoir 151 for the pump 55. 40

An automatic cycle of operation is initiated by rotating the hand lever 23 through an arc of substantially 20°. This will cause rotation of the 45 shaft 108 through the same angle and thereby rotation of a cam 152 fixed to the shaft 108. The plunger 153 of the pilot valve 121 is held in engagement with the periphery of this cam by a spring 154. When the parts are in the starting 50 position shown in Figure 8, the pressure port 120 is connected by cannelure 155 to port 156 and thereby through channel 157 to the right hand port 158 of the reversing valve 123, shifting the plunger 124 to the left. As the plunger 153 of 55 the pilot valve moves toward the right under the action of cam 152 during clockwise rotation thereof, the port 120 will be connected through cannelure 159 to port 160 whereby fluid pressure will flow through channel 161 to the left hand port 162 of the reversing valve 123 shifting the plunger 124 thereof to the right. This will establish the previously described pressure connections to the cylinder 104 and from there on the cycle will continue automatically. 60

The shaft 108 has a second cam 163 attached thereto against the periphery of which the plunger 130 of the regenerative valve is held by a spring 164. The cam 163 has a profile surface 165 which is of constant radius throughout most 70 of the rotation of shaft 108 but near the end of the stroke there is a sudden rise which shifts the plunger 130 toward the right a sufficient distance to uncover the pressure port 129. The result is that fluid pressure will flow into the 75

space 166 and act on the differential areas 167 and 168 of the plunger. The resultant differential pressures will fire plunger 130 toward the right against the compression of spring 164. The firing of this valve will take place at the time that the servo-motor piston 51 in Figure 7 has reached the end of its stroke and rotated the cam 86 the maximum amount and thus completed the movement of the grinding wheel toward the work. Any subsequent advance of the piston 105 will merely effect a greater separation between the parts of the servo-control valve and thereby increase the pressure in the end of cylinder 50 without causing further movement.

15 When the regenerative valve plunger 130 is fired, it must remove the fluid in the space 169 in the right hand end of the valve casing and this fluid will readily pass through exhaust port 170 until it is closed. Further movement will depend upon the rate of escape through a channel 171 which is connected to the extreme end of the space 169 and leads to port 172 of a tarry control valve 173. This valve has a plunger 174 which is held by a spring 175 against the end 20 of an adjusting shaft 176 which is threaded at 177 in the valve housing. A knurled knob 178 secured to the end of the shaft 176 serves as means for effecting adjustment of the valve.

30 The plunger 174 has a spool 179 which is movable relative to the port 172 and in the spool is formed a V-shaped notch 180 which acts as an hydraulic resistance to vary the back pressure in the channel 171 and thereby in the space 169. This hydraulic resistance will determine the rate of escape of fluid into an annular groove 181 formed in the plunger which is connected by an open port 182 to the return line 150 and thereby the length of tarry between the termination of the forward movement and the 40 beginning of the return movement.

45 When the regenerative valve plunger 130 has completed its shifting movement, the pressure port 128 will be connected to the motor port 116, and the motor port 117 will be connected to the exhaust port 170. This will cause return movement of the piston 105. Since the supply fluid will be coming directly from the pump 55 and the return fluid will be returning directly to reservoir through the low pressure relief valve 58, the return movement will be at a rapid traverse rate.

50 Although the cam 163 will be rotating in a direction to reduce its effective radius during this return movement, the plunger 130 of the regenerative valve will still be held in a right hand position due to differential pressure in space 168 and cannot be returned until this pressure is broken.

55 As the shaft 108 returns counterclockwise, the rise on cam 152 is decreasing, permitting the plunger 153 to move toward the left under pressure of spring 154 and this will continue until the valve has moved a sufficient distance to interconnect the pressure port 120 with port 156. 60 When this happens the reversing valve plunger 124 will be fluid shifted to the left to connect channel 127, which is supplying fluid pressure to the space 166 of the regenerative valve to reservoir.

65 This shifting movement will be delayed, however, by a choke coil 159 which is connected to port 160 of the pilot valve. In other words, the exhaust of fluid from the left end of the reversing valve will be delayed whereby the shaft 108

will continue to rotate and thus have time to return the control lever 23 to its starting position, before the reversing valve shifts a sufficient distance to release the holding pressure on the regenerative valve.

70 When the pressure in chamber 166 is dissipated, the spring 164 returns the plunger 130 to its left hand position whereby the motor port 116 will be reconnected to port 132 and motor port 117 will be connected to the port 128. Since port 128 is disconnected from pressure at this time, the cycle of operation will stop.

75 It will be understood that the return movement of piston 105 will rotate the cranks 107 and 109 in a counterclockwise direction and thereby through the servo-motor control valve cause return movement of piston 51. When the regenerative valve returns to its normal position, fluid pressure will be cut off from cylinder 104 whereby a manual movement of the manual control lever 23 will be necessary to initiate another cycle of operation.

80 The "run ahead" valve 140 is provided for the purpose of permitting the operator at will to move the grinding wheel toward the work piece 25 at a faster rate than that determined by the rate valve 138. This is accomplished by providing a plunger 184 which is normally held in a position to disconnect the left hand end of cylinder 185 in which the plunger is slidable from ports 186 as 30 mentioned supra. The channel 136 through which the fluid flows from the left hand end of cylinder 104 to reservoir is connected in parallel to ports 137 and 139. The port 139 is in communication with the space 185 so that whatever 35 pressure exists in channel 136 is constantly acting on the end of plunger 184 tending to shift the same toward the right. This movement is opposed by a spring 187 which is interposed between the end of the valve housing and a cup-shaped 40 piston 188 which engages the end of plunger 184. The spring is assisted by fluid pressure from the pressure supply line 119 which is connected through a hydraulic resistance 189 to the space 190 which contains the spring. The piston 188 45 has a small coaxial hole formed therein whereby the fluid pressure in the space 190 may flow into the space 191 on the other side of the piston. This would tend to equalize the pressure on opposite sides of the piston but due to the dash pot 50 effect it should damp out sudden movements of the piston 188. Should the operator exert continuous pressure on the handle 23 after the automatic cycle has started, he would increase the back pressure in the left hand end of cylinder 55 104 and thereby increase the pressure in the space 185 which would cause movement of the plunger 184 toward the right a sufficient distance to interconnect port 139 to the exhaust line 150 whereby there would be a sudden release of 60 pressure and an acceleration in the movement of piston 105.

65 Upon release of excessive pressure on handle 23 the pressure in space 185 will immediately decrease, thereby permitting the spring 187 to close the port 186 whereby future discharge of the fluid to reservoir must pass through the rate control valve.

70 The automatic cycle actuating mechanism shown in Figure 10 may be rendered inoperative by a cut-out valve 192 which has a rotatable plunger 193 whereby upon rotation of the plunger through 90° from the position shown, the channels 114 and 115 will be interconnected by 75

an axial groove 194 to an exhaust groove 195, thereby releasing the pressure on both ends of cylinder 104 and permitting operation of the servo-valve without interference from this piston. It is, of course, obvious that the linkage could be disconnected to break the connection of the motor 104 with the servo-valve.

There has thus been provided an improved form of infeed mechanism which may be built as a separate unit for attachment to any suitable form of machine tool which has a manually operable infeeding cycle and which it may be desired to operate automatically.

What is claimed is:

1. In a machine tool having a work support and a tool support and a power operable mechanism for effecting an infeed cycle between the supports including a manual control, the combination of a one-cycle driving and timing mechanism for said control, including a rotatable shaft,

motion transmitting connections from said shaft to said control, a power operable motor for rotating said shaft, a source of fluid pressure for said motor, and means responsive to a prescribed angular movement of the manual control from a prescribed starting position to connect said source of pressure to said motor to initiate an automatic cycle of movement of said manual control.

2. In a machine tool having a work support

and a tool support and a power operable mechanism for effecting an infeed cycle between the supports including a manual control, the combination of a one-cycle driving and timing mechanism for said control, including a rotatable shaft,

motion transmitting connections from said shaft to said control, a power operable motor for rotating said shaft, a source of fluid pressure for said motor, means responsive to a prescribed angular movement of the manual control from a

starting position to connect said source of pressure to said motor to initiate an automatic cycle of movement of said manual control, and means to control the rate of flow of fluid pressure to said motor and thus determine the timing of said cycle.

3. In a machine tool having a work support and a tool support and power operable mechanism for effecting an infeeding cycle between the supports, including a manual control, the combination of a one-cycle driving and timing mechanism for said control, including a rotatable shaft,

a power operable motor for rotating said shaft, a source of fluid pressure for said motor, motion transmitting connections from said manual control to said shaft whereby said shaft will be initially actuated by said control, means responsive to the initial rotation of said shaft to connect said source of fluid pressure to said motor whereby subsequent rotation of said shaft will

be effected by said motor to effect an automatic cycle, and additional means responsive to rotation of said shaft for disconnecting said source of fluid pressure from said motor automatically.

4. In a machine tool having a work support and a tool support and a servo-motor mechanism operatively connected to one of said supports for moving the same toward and from the other support including a servo-valve, and a manual control, whereby any movement of the manual control will result in movement of the slide; the combination of a one-cycle driving mechanism for said manual control which will automatically effect advance and retractive movements thereof in predetermined timed relation, including a fluid

operable motor operatively connected to said

manual control, a source of pressure, valve means for connecting said source of pressure to said motor, and additional valve means for disconnecting said source of fluid pressure from said motor, both of said valve means being operable in timed relation to the rate of actuation of said motor.

5. In a machine tool having a work support and a tool support and cam means operatively connected for effecting approach and retractive movements between said supports upon opposite actuation of said cam, the combination of a fluid operable motor mechanically connected for actuation of said cam, a servo control valve for governing the admission of fluid pressure to said cylinder, said servo-valve having a manual control, a second fluid operable motor for oscillating said manual control, automatic timing mechanism for said motor whereby it will effect movement of said manual control at a predetermined rate during one direction of movement, means automatically operable for reversing the direction of movement of said last named motor, means for delaying the starting of said reversing movement, and means for causing said return movement to be effected at a rapid traverse rate.

6. The combination with an infeeding mechanism for a machine tool, said mechanism having a unitary control for effecting one complete cycle of movement, of a power driving and timing mechanism for said control, including a fluid operable motor operatively connected to said control, a source of pressure for said motor, means operable after a predetermined manual movement of said control to effect a pressure connection to said motor, means responsive after a predetermined advancing movement of said motor to disconnect the pressure therefrom and cause a tarry, automatic means for determining the length of said tarry and subsequent reverse connection of pressure to said motor, said power return movement of the motor being of greater length than the power advancing movement.

7. In a machine tool having a servo-motor mechanism for effecting relative movement between a grinding wheel and a work piece, the combination with a servo-valve control therefor, of a fluid operable motor for reverse actuation of said servo-valve, a source of fluid pressure for said motor, cam operated valve means for connecting said source of pressure to said motor to effect one direction of actuation thereof, a pressure differential operated valve for reversing said motor, means operable by said motor for creating said pressure differential to effect shifting of said valve, and adjustable means for determining the rate of said shifting of said valve and thereby the length of tarry between the advance and return of said motor.

8. In a grinding machine having a work support and a grinding wheel support, and a servo-motor mechanism for effecting a relative infeeding movement between said supports, said servo-motor mechanism including a servo control valve having a manually operable control, the combination of a power driving and timing mechanism for oscillating said control, including a fluid operable motor, motion transmitting connections from said motor to said control, a source of fluid pressure, cam operable valve means effective upon rotation of said control to connect the source of fluid pressure to said motor to effect automatic actuation thereof, adjustable means for controlling the rate of said actuation, a regenerative control valve for reversing the connections to said

- motor, cam operated means for determining the time of firing of said valve, and motion transmitting connections coupling said motor to each of said cam means.
5. 9. In a grinding machine having a grinding wheel support and a work support, one of which is movable relative to the other to effect an in-feeding grinding cycle, the combination with power operable means for effecting said movement, including a control valve having a manually operable handle, the combination of a shaft, a fluid operable motor for rotating said shaft, motion transmitting connections from said shaft to said control, means to rotate said shaft upon actuation of said control handle, cam operated valve means for connecting the source of fluid pressure to said motor, a cam therefor carried by said shaft whereby after a predetermined manual movement the shaft will be power rotated automatically, additional cam means carried by said shaft, and valve means actuatable by the last named cam means for reversing the pressure on said motor and causing return rotation of said parts.
25. 10. In a machine tool having a work support and a tool support, and a servo-motor mechanism operatively connected to one of said supports for moving the same toward and from the other support, including a servo-valve, and a manual control therefor, whereby any movement of the manual control will result in servo-motor actuation of the movable support; the combination of a one-cycle driving mechanism for said manual control including a fluid operable motor mechanically connected to said manual control, a source of fluid pressure for said motor, a control valve fluid shiftable to one position to connect said source of pressure to said motor, and to a second position for disconnecting said source of pressure from said motor, a pilot valve therefor, means actuatable upon initial movement of said manual control to shift said pilot valve and thereby fluid position said control valve in a running position, and means operable by said motor to fluid position said control valve in its other position.
11. In a machine tool having a work support and a tool support, and a servo-motor mechanism operatively connected to one of said supports for moving the same toward and from the other support, including a servo-valve, and a manual control therefor, whereby any movement of the manual control will result in servo-motor actuation of the movable support; the combination of a one-cycle driving mechanism for said manual control including a fluid operable motor mechanically connected to said manual control, a source of fluid pressure for said motor, a control valve fluid shiftable to one position to connect said source of pressure to said motor, and to a second position for disconnecting said source of pressure from said motor, a pilot valve therefor, means actuatable upon initial movement of said manual control to shift said pilot valve and thereby fluid position said control valve in a running position, said pilot valve being subsequently oper-
- able by said motor to fluid position said control valve in its other position, and hydraulic resistance means for delaying the last named shifting of said control valve.
12. In a machine tool having a work support and a tool support, the combination with a first fluid operable motor mechanically connected for effecting relative movement between said supports, of a control valve including relatively movable parts for governing the rate and direction of fluid flow to said motor, one part of said valve having a manual control, a feed-back connection from the motor to the other part of said valve, a second fluid operable motor mechanically connected to said manual control for effecting automatic cyclic movement thereof, a rate and direction control and timing circuit for said last named motor, and a valve for disconnecting said second motor from said circuit whereby said manual control may be utilized for set-up purposes without interference from the last named motor.
13. In a machine tool having a work support and a tool support, the combination of mechanism for effecting relative movement between the supports, including a pair of parallel shafts, an in-feeding cam for the movable support carried by one of said shafts, hydraulic motors of the piston and cylinder type operatively connected to each of said shafts, a control valve for one motor including relatively movable parts, one of which is connected to one shaft and the other of which is connected to the other shaft, a manual control lever for one of said parts, a source of pressure connected to said control valve whereby servo operation of the connected motor may be effected by the manual control, and valve means for connecting said source of pressure to the other of said motors, said last named valve means being operable by a cam attached to the other of said shafts, whereby a predetermined angular movement of said manual control will cause subsequent automatic operation of said servo operation.
14. In a machine tool having a work support and a tool support, and a servo-motor mechanism operatively connected for effecting relative movement of one of said parts toward and from the other, including a servo-valve having a manual control, the combination of a fluid operated means for driving said manual control through a predetermined cycle of operation, including a fluid operable motor, linkage connecting said motor to said manual control, a source of pressure, a starting valve for connecting said source of pressure to said motor, a pilot valve for effecting fluid shifting of said starting valve, a pressure differential shiftable reversing valve, a supply channel from said starting valve terminating in a pair of ports in said last named valve, means in the reversing valve for connecting one of said ports to said motor, and additional means in the valve responsive to mechanical shifting thereof to connect the other port for pressure differential shifting of the valve and thereby reversal of the motor.
